(57) **CLAIM**

The ornamental design for an architectural panel with translucent wood design, as shown and described in the Figures.

DESCRIPTION

FIG. 1 is a facing perspective view of an architectural panel portion incorporating the translucent wood design as used in a partition structure;

FIG. 2 is a close up view thereof;

FIG. 3 is a front elevational view thereof, the rear elevational view being a mirror image thereof;

FIG. 4 is a cross-sectional view of FIG. 3, taken along line 4—4 in FIG. 3;

FIG. 5 is a cross-sectional view of FIG. 3, taken along line 5—5 in FIG. 3;

FIG. 6 is a cross-sectional view of FIG. 3, taken along line 6—6 in FIG. 3;

FIG. 7 is a cross-sectional view of FIG. 3, taken along line 7—7 in FIG. 3; and,

FIG. 8 is an enlarged cross-sectional view shown along line 7—7 in FIG. 7.

The broken lines showing environment in the drawings are included for illustrative purposes only and form no part of the claimed design. The outer broken line boundaries in Figures depicting the boundaries of the claimed design indicate that a specific length width and shape form no part of the claimed design and are for illustrative purposes only.
